UNITED STATES PATENT OFFICE.

MABEL L. PHINNEY, OF FERGUS FALLS, MINNESOTA.

DESIGN FOR A DOLL.

Application filed January 5, 1923. Serial No. 4,819. Term of patent 7 years.

To all whom it may concern:

Be it known that I, MABEL L. PHINNEY, a citizen of the United States, residing at Fergus Falls, in the county of Otter Tail and State of Minnesota, have invented a new, original, and ornamental Design for a Doll, of which the following is a specification, reference being had to the accompanying drawings, forming part thereof.

I claim:

The ornamental design for a doll, as shown.

MABEL L. PHINNEY.
